UNITED STATES PATENT OFFICE.

JOHN J. CATRON, OF BONHAM, TEXAS.

LIQUID STORAGE AND DISPENSING APPARATUS.

1,352,788.

Specification of Letters Patent. Patented Sept. 14, 1920.

Application filed May 2, 1919. Serial No. 294,277.

To all whom it may concern:

Be it known that I, JOHN J. CATRON, a citizen of the United States, residing at Bonham, in the county of Fannin and State of Texas, have invented certain new and useful Improvements in Liquid Storage and Dispensing Apparatus, of which the following is a specification.

This invention relates to new and useful 10 improvements in liquid storage and dispensing apparatuses:

The purpose of the invention is to provide an air pressure system of storage and discharge for inflammable liquids which involves a high factor of safety and a positive 15 means of discharge as well as efficient and economical operation.

In carrying out the invention a storage tank is united with a pressure tank. The 20 storage tank has a filling inlet provided with a means of limiting the quantity of liquid stored, whereby ample space is left in the storage tank to accommodate the contents of the pressure tank, should 25 said contents be displaced into the storage tank. A feature of importance is a discharge of liquid from the pressure tank and precluding the possibility of the compressed air entering the liquid discharge pipe. An 30 other feature is that all the openings are in the top of the storage tank and all the pipes, valves and controls are wholly within the tanks and accessible through the top of the storage tank.

35 The invention will be more readily understood from a reading of the following specification and by reference to the accompanying drawings, in which an example of the invention is shown and wherein:

40 Figure 1 is a view of an apparatus constructed in accordance with the invention, partially in elevation and partially in section,

Fig. 2 is a vertical sectional view of the 45 same, and

Fig. 3 is a sectional detail showing the opened and closed positions of the displacement valve.

In the drawings the numeral 1 designates 50 a storage tank having a man-hole 2 at the center of its top. A pressure tank 3 is united to the bottom of the tank 1 at the center thereof and closed by dished cap 4 which forms part of the bottom of the tank 55 1. A filling collar 5 is made at the top of

the tank 1 and a filling pipe 6 extends down to a point above the bottom of the storage tank. A bracket arm 8 is supported on the lower end of the pipe and has one end of a horizontal lever 9 pivoted thereto. The 60 arm carries a valve 7 hinged thereon and adapted to seat against the bracket and seal the pipe when the arm is swung up. The outer end of the arm is pivoted to the lower end of a rod 10 extending up through a 65 bracket 6' on the pipe 6. A float 11 is fastened on the upper end of the rod and its descent is limited by the bracket. It will be seen that when the tank has been filled to a level above the bracket the float will rise 70 therefrom and seat the valve 7 so that no more liquid can enter the tank 1. The level attained leaves a space at the top of the tank 1 at least equal to the capacity of the pressure tank; and thus should the pressure 75 tank overflow the contents will be accommodated in the storage tank.

At the center of the top of the pressure tank a nipple 17 is secured and receives a cap 16. A tube 15 mounted in the cap depends into the pressure tank and carries a valve casing 12 above the cap. A check valve 14 is hinged in the casing so as to swing in to admit fluid from the tank 1 and to close to prevent a reverse flow. A nut 13 80 closes the top of the casing and may be removed to give access to the valve. A compressed air pipe 18 leads through the top of the storage tank down to the cap 16 so as to discharge compressed air into the pressure tank. A discharge pipe 19 leads from a point above the bottom of the tank 3 up through the cap 16 to the top of the tank 1. The tank 1 is also provided with a vent 90 in its top.

On the lower end of the pipe 19 a collar 21 is secured. A displacement valve 22 is hinged to the collar. A float lever 23 is pivoted to the under side of the valve and has its longer end bent upward at an angle. 100 A float member 25 is fastened to the angular end of the lever; while a similar member 24, but much smaller, is fastened to the short end of the lever. When the liquid in the tank 3 falls to a low level the member 25 being slightly heavier swings down and thus seats the valve 22 against the collar 21. However when the pressure tank is filled with liquid the member 25 being considerably larger than the member 24 is displaced 105 110

upward owing to its greater liquid displacement, thus holding the valve open. A valve casing 26 is included in the pipe 19 in the tank 3. This casing contains a check valve 27 which opens upward to permit the discharge of liquid but seats to prevent a reverse flow.

It will be seen that compressed air, being admitted to the pressure tank from the pipe 18, will enter the tube 15 and seat the valve 14. The valve 22 being open, liquid in the pressure tank will thus be forced out through the pipe 19. With the valve 14 seated no air can enter the storage tank. As soon as the air is cut off from the pressure tank the liquid will stop discharging and when the pressure is relieved the check valve 27 will seat thus preventing the liquid in the pipe 19 above said valve from flowing back into the tank. When the liquid in the pressure tank is above the low level the displacement valve will occupy the position shown in dotted lines in Fig. 3, but when said liquid reaches the low level the valve will close as is shown in full lines in Figs. 1 and 3 thus preventing air entering the discharge pipe 19, the lower end of which is at all times immersed. The air pressure being cut off, the liquid in the storage tank will unseat the valve 14 and fill the pressure tank.

What I claim, is:

1. A liquid storage and dispensing apparatus, comprising a storage tank, an inlet pipe leading into the storage tank, a valve to close the inlet pipe, float controlled means to close the valve when the liquid reaches a predetermined level in the storage tank for permanently maintaining a space in the upper portion of the storage tank, a pressure tank arranged near the storage tank, a supply pipe having one end leading into the pressure tank and its opposite end leading into the storage tank, a check valve to close the supply pipe and seated by pressure within the pressure tank, an outlet pipe

leading into the pressure tank, float control means to close the outlet pipe and arranged within the pressure tank, and a pressure supply pipe leading into the pressure tank.

2. A liquid storage and dispensing apparatus, comprising a storage tank, an inlet pipe extending into the storage tank and having its lower end arranged near the bottom of the storage tank, a valve to close the outlet end of the inlet pipe, a float arranged within the storage tank and connected with the valve and adapted to close it when the liquid level in the storage tank reaches a predetermined height for maintaining a permanent space in the top of the storage tank, a pressure tank arranged beneath the storage tank, a supply pipe having its lower end within the pressure tank and its upper end within the storage tank, a check valve within the supply pipe and closing toward the upper end of the supply pipe and being seated by pressure in the pressure tank, an outlet pipe leading into the pressure tank and having a check valve, a float controlled valve to close the intake end of the outlet pipe, and a pressure supply pipe leading into the pressure tank.

3. A liquid storage and dispensing apparatus, comprising a storage tank having an opening in its lower portion, means for supplying a liquid to the same, a pressure tank having its upper end secured within the opening of the storage tank, a head closing the upper end of the pressure tank and provided with an upstanding nipple, a cap arranged upon said nipple and having a flange to engage therewith, a supply pipe carried by the cap and extending above and below it within the storage and pressure tanks, an outlet pipe passing through said cap, and leading into the pressure tank, means to close the outlet pipe, and a pressure supply pipe connected with the cap and leading into the pressure tank.

In testimony whereof I affix my signature. JOHN J. CATRON.
